UNITED STATES PATENT OFFICE.

JOHN WILLIAM HASSELKUS, OF LONDON, ENGLAND, ASSIGNOR TO THE
ROSS, LIMITED, OF SAME PLACE.

PRISMATIC BINOCULAR GLASSES.

SPECIFICATION forming part of Letters Patent No. 659,526, dated October 9, 1900.

Application filed August 10, 1900. Serial No. 26,499. (No model.)

To all whom it may concern:

Be it known that I, JOHN WILLIAM HASSELKUS, a subject of the Emperor of Germany, and a resident of 3 North Side, Clap-
ham Common, London, England, have in-
5 vented certain new and useful Improvements
in Prismatic Binocular Glasses, (for which a
British patent has been applied for, No.
12,538, dated July 11, 1900,) which invention
10 is fully set forth in the following specifica-
tion.

The object of this invention is to construct
prismatic binocular glasses so that their
prisms can be readily adjusted for coinci-
15 dence of the images seen through the two
eyepieces and so that the instrument is not
liable to become disarranged in ordinary use
after adjustment, the construction generally
being improved and simplified and al-
20 lowing of simultaneous longitudinal move-
ment of the tubes carrying the eyepieces
being effected by means of a central screw
without interfering with the facility with
which the testing and adjustment of the
25 prisms can be effected. The binoculars to
which this invention relates are such as have
the two body parts hinged together by con-
necting-plates, so that the distance between
the eyepieces can be altered to suit different
30 users.

In the accompanying drawings, Figure 1
represents in side view, with the mid-part in
section, a binocular glass made in accordance
35 with this invention. Fig. 2 is an end view.
Fig. 3 shows the body parts and their hinged
connection separately from the eyepieces and
tubes and the adjusting-screw, which are
shown in Fig. 4.

A are the body parts of the instrument, car-
40 rying the objectives and the prisms, and B
are the tubes carrying the eyepieces. The
body parts A have secured to their ends the
plates a, which are provided with tubes for
the objectives at one end and for the eye-
45 piece-tubes at the other end, the said body
parts A being connected together by hinge-
joints consisting of parts a², cut away so as
to overlap each other and secured together
by collets a³, connected by the screws a⁴.
50 The tubes B are connected together by the
bars b, similarly hinged together by cut-away

and overlapping parts b², secured by the col-
lets b³, one on the screw-stem C and one on
the other side, these collets being secured to-
gether by the screw b⁴. The screw c, carried
55 by the screw-stem C, engages in a screw-nut
carried by the hollow shaft D, which carries
a milled head d² and is secured against longi-
tudinal movement by a screw or screws e, se-
cured through the sleeve E and engaging with
60 the said shaft D. The sleeve E is confined
between the upper and lower inner collets
and is held in position by the hollow shaft D
and by an end piece d³, which is engaged by
a pin f² at the end of the screw f. g and g²
65 are the ordinary plate and spring-catch ar-
rangement, the catch engaging in a notch
in the plate for indicating the proper adjust-
ment to suit any particular user; but these
need not be employed unless desired. The
70 frictional bearing of the sleeve E, hollow
shaft D, and screw-stem C, and of the collets
b³, with the orifice through the hinged arms
b, are respectively such as to allow the nut
d to rotate to operate the screw for longitu-
75 dinal adjustment; but overwinding of the
screw will not cause injury to the parts, as if
the operation of the milled head d² be con-
tinued after the screw is fully moved longi-
tudinally in either direction the said screw-
80 stem C, hollow shaft D, and sleeve E will ro-
tate together by the rotation of the stem C
and collets in the orifice through the hinge
of the arms b. In order to insure proper fric-
tional contact between the arms b and the
85 collet b³, the said collet may have in its face
next the arms a groove, in which a spring
may be placed, so as to bear against the arms
and compensate for any wear between the
parts in contact.

To adjust the instrument for coincidence
of the images of the two eyepieces, the screw f
is removed and also the screw e, and then the
parts shown in Fig. 4 can be removed length-
wise, and the sleeve E can also be taken out
90 sidewise, and then the bodies A of the instru-
ment, hinged together, are free of the other
parts, as shown in Fig. 3, and can be placed
in the adjusting instrument, which will have
center pivots or pins to truly fit into the open-
95 ings through the collets a³ of the hinges, and
a telescopic arrangement and crosswise im-

ages in a line truly parallel with the line of the said pivots are viewed and the prisms adjusted, and when adjustment of the prisms is effected the parts are all secured together again, as shown in Figs. 1 and 2.

Having now particularly described and ascertained the nature of the said invention and in what manner the same is to be performed, I declare that what I claim is—

- 10 A prismatic binocular glass consisting of body parts provided with connecting-plates hinged together by centrally - perforated hinges and eyepiece - tubes connected together by a similarly - perforated hinge, a
- 15 screw-stem secured in the perforation of the last-named hinge, a hollow shaft secured centrally with the perforations of the hinges and provided with a milled head and a screw-nut

for engaging the screw on the said screw-stem and a sleeve also secured centrally with the perforations of the hinges by a securing device and connected with the shaft by a securing device so as to be capable of being removed from between the hinged arms of the body parts when the securing devices are removed and the screw-stem and hollow shaft are withdrawn all substantially as hereinbefore described.

In testimony whereof I have signed this specification in the presence of two subscribing witnesses.

JOHN WILLIAM HASSELKUS.

Witnesses:

WILLIAM JOHN WEEKS,
JOHN EDWARD NEWTON.
